T. B. KEOGH.
CUSHION HEEL.
APPLICATION FILED JUNE 22, 1916.

1,202,732.

Patented Oct. 24, 1916.

UNITED STATES PATENT OFFICE.

THOMAS B. KEOGH, OF NEW YORK, N. Y., ASSIGNOR OF ONE-FOURTH TO FREDERICK P. AUWELL, OF BROOKLYN, NEW YORK, AND ONE-FOURTH TO NICHOLAS P. WEDIN, OF JERSEY CITY, NEW JERSEY.

CUSHION-HEEL.

1,202,732.

Specification of Letters Patent. Patented Oct. 24, 1916.

Application filed June 22, 1916. Serial No. 105,189.

To all whom it may concern:

Be it known that I, THOMAS B. KEOGH, a citizen of the United States, residing at Bronx, New York city, in the county of 5 New York and State of New York, have invented certain new and useful Improvements in Cushioned Heels; and I do hereby declare the following to be a full, clear, and exact description of the invention, such as 10 will enable others skilled in the art to which it appertains to make and use the same.

The invention relates to improvements in cushioned heels.

The object of the present invention is to 15 improve the construction of cushioned heels and to provide a simple, practical and comparatively inexpensive construction adapted to be readily applied to various types of foot wear and capable of absorbing and dissipating 20 shocks and of lessening the fatigue of walking and running and of minimizing the jar.

With these and other objects in view, the 25 invention consists in the construction and novel combination of parts hereinafter fully described, illustrated in the accompanying drawing, and pointed out in the claims here-to appended; it being understood that various changes in the form, proportion, size 30 and minor details of construction, within the scope of the claims, may be resorted to without departing from the spirit or sacrificing any of the advantages of the invention.

35 In the drawing Figure 1 is a vertical longitudinal sectional view of a cushioned heel constructed in accordance with this invention and shown applied to a portion of a shoe, Fig. 2 is a transverse sectional view of 40 the same taken substantially on the line 2—2 of Fig. 1, Fig. 3 is a horizontal sectional view on the line 3—3 of Fig. 1, Fig. 4 is a detail view of the marginal cushioning spring, Fig. 5 is a vertical sectional view 45 illustrating a modification of the invention, Fig. 6 is a transverse sectional view of the same, Fig. 7 is a plan view of the metallic plate of the lower relatively movable heel section for interlocking the same with the 50 headed stud.

Like numerals of reference designate corresponding parts in the several figures of the drawing.

In the accompanying drawing in which is

illustrated the preferred embodiment of the 55 invention, the cushioned heel comprises in its construction, a metallic shell 1 constituting the upper portion of the heel and consisting of a horizontal top plate 2 and vertical walls 3, the top plate being provided 60 with suitable perforations for the reception of fastening devices 4 which secure the cushioned heel to a shoe 5 or other foot wear. The metallic shell telescopically receives a lower heel section 6 designed to be 65 constructed of leather or other suitable material and cushioned by coiled conical springs 7 and a marginal spring 8. The upper and lower heel sections conform to the configuration of the conventional heel and the upper metallic heel section is equipped with a plurality of depending headed studs 9 secured at their upper ends 10 to the top plate 2 and extending downwardly therefrom and provided at their lower ends with heads 11. 70 The lower heel section is provided with vertical sockets 12 extending downwardly from the upper face of the lower heel section and receiving the headed fastening devices which are adapted to be engaged by a locking plate 75 13. The locking plate 13 is constructed of suitable sheet metal and is fitted in a recess or pocket 14 of the lower heel section and is provided with slots 15 and 16 which are adapted to receive the shank portions of the 80 headed studs.

In applying the locking plate the heel is forced inwardly sufficiently to compress the coiled springs which bear against the upper face of the lower heel section. The springs 90 are compressed to cause the heads of the fastening devices to extend below the horizontal recess or pocket 14 and the locking plate is then inserted in the recess or pocket and engaged with the headed stud. By this construction the upper and lower heel sections are securely connected together and the locking plate is retained against accidental displacement by a flange 17 formed integral with and extending downwardly from the 100 front portion of the locking plate and secured to the heel section 6 by suitable fastening devices 18. When the heel is subjected to pressure the springs will be placed under tension and the cushioning action is 105 increased by a marginal spring 19 constructed of resilient wire or other suitable material and composed of spaced sides and

connected transverse portions as clearly illustrated in Fig. 4 of the drawing. The marginal spring is composed of reversely arranged approximately U-shaped spring 5 bends 20. The marginal spring conforms to the configuration of the heel and one or more of the springs may be omitted to secure the desired cushioning action and the strength of the springs may of course be 10 varied. The approximately U-shaped or V-shaped bends form oppositely inclined portions 21 and provide an effective cushioning device.

In Figs. 5 to 7 inclusive of the accompanying drawing is illustrated another form of the invention in which elastic cushioning sleeves 22 are mounted on the headed fastening devices instead of conical coiled springs and the lower section 23 is slidably 20 interlocked with the headed fastening devices 24 being provided with substantially key-hole shaped openings 25 formed in a metallic plate 26 which is mounted within the lower heel section 23. The sockets 27 25 of the lower heel section are elongated to enable the slotted locking plate 26 to be engaged with the headed fastening devices and the outer shell is preferably provided with lugs 29 which are bent around into 30 engagement with the lower heel section to hold the same against relative sliding movement. The cushioned heel shown in Figs. 5 to 7 inclusive is also provided with a marginal spring 19 and the said locking plate is 35 preferably secured between the layers of lifts of the lower heel section.

The cushioned heel is adapted to be readily applied to a boot or shoe and by varying the strength of the cushioning springs 40 and the number thereof the desired resiliency and cushioning action of the heel may be obtained.

What is claimed is:—

1. A cushioned heel of the class described 45 including an upper metallic shell, a lower relatively movable section provided with sockets and having a pocket or recess intersecting the same, headed studs depending from the metallic shell and extending into

the sockets, a locking plate removably arranged in the pocket or recess and interlocked with the headed studs, and cushioning devices disposed on the headed studs and interposed between the lower heel section and the metallic shell. 55

2. A cushioned heel of the class described including an upper section, a lower relatively movable section, one of the sections consisting of a metallic shell and receiving the other section and a marginal spring 60 interposed between the sections and composed of spaced sides and connecting transverse portions and consisting of a resilient piece of material bent to form reversely disposed spring bends of approximately V- 65 shape.

3. A cushioned heel of the class described including an upper metallic shell having depending studs, a lower heel section slidably interlocked with the said studs, cushionings arranged on the studs and interposed between the shell and the lower heel section and a marginal cushioning spring extending around the studs and consisting of a continuous piece of resilient material bent 75 back and forth to form reversely arranged approximately V-shaped spring bends. 70

4. A cushioned heel of the class described including an upper inverted metallic shell, a lower heel section provided with elongated sockets and having a metallic plate provided at the sockets with substantially key-hole shaped openings, headed studs depending from the metallic shell and extending into the elongated sockets and interlocked with the key-hole slot, cushioning means interposed between the lower heel section and the metallic shell, and means carried by the metallic shell and engaging the lower heel section for holding the same 90 against sliding movement. 80

In testimony whereof I affix my signature in presence of two witnesses.

THOMAS B. KEOGH.
